UNITED STATES PATENT OFFICE.

HARRY PAULING, OF GELSENKIRCHEN, GERMANY, ASSIGNOR TO THE FIRM OF SALPETERSÄURE-INDUSTRIE-GESELLSCHAFT G. M. B. H., OF COLOGNE, GERMANY.

ELECTRIC FURNACE FOR PRODUCING GAS REACTIONS.

1,029,886.

Specification of Letters Patent.

Patented June 18, 1912.

Application filed October 24, 1911. Serial No. 656,471.

To all whom it may concern:

Be it known that I, HARRY PAULING, a subject of the King of Prussia, residing at Gelsenkirchen, in the Kingdom of Prussia and German Empire, have invented new and useful Improvements in Electric Furnaces for Producing Gas Reactions, of which the following is a specification.

This invention relates to electric furnaces for producing gas reactions; and it comprises suitably arranged main electrodes and igniting or starting electrodes, and means for water-cooling said igniting electrodes, such water-cooling means being also best arranged in connection with means for water-cooling said main electrodes; all as more fully hereinafter set forth and as claimed.

In establishing electric arcs suitable for use in gas reactions as, for example, in the manufacture of nitrogen oxids from air, it is convenient to employ adjustable auxiliary igniting or starting electrodes in connection with the main electrodes in order to avoid the use of excessively high initial voltage which would otherwise be necessary to strike an arc directly across the air gap between the electrode terminals. These igniting or starting electrodes have heretofore been so arranged that they become intensely heated by the hot gases in the furnace, in consequence of which they lose their stiffness, become liable to bend, and thus give rise to disturbances. In order to avoid these difficulties and to attain certain added advantages, I provide means for cooling the igniting electrodes without in any way interfering with their freedom of adjustment. For example, each starting electrode may be laterally inclosed by a water jacket which is best arranged to fit said electrode as closely as is consistent with free longitudinal adjustment of the electrode therein. Since it also is advisable to cool the main as well as the auxiliary electrodes, it is convenient to connect the cooling jacket of an igniting electrode with the cooling means for an adjacent main electrode. The main electrodes may be hollow, and cooling water may thus be circulated through them internally from the water jackets of their respective auxiliary electrodes, or vice versa. A very convenient method of arrangement and one which is preferred herein, is to provide within the conduit through which cooling water is supplied to the main electrode, a tube or hol-

low sleeve within which is slidably mounted the igniting electrode. The annular space between the tube and the conduit serves as a jacket wherein water cools the igniting electrode externally and then passes on to the main electrode which, in the example supposed, is cooled internally. A unitary and compact cooling system is thus provided for preventing undue heating of either the main or the auxiliary electrodes.

In the accompanying drawings, I have shown diagrammatically an assemblage of apparatus elements embodying the present invention. For purposes of illustration the invention is shown as applied to diverging electrodes.

In this showing, Figure 1 is an elevation of an arrangement of electrodes under the present invention, parts being shown in section; and Figs. 2 and 3 are cross-sections on the lines A—B and C—D, respectively, of Fig. 1.

Referring to the drawings, the igniting electrode *a* is inclosed in a tube *b* which is surrounded by a second tube *c*. In the space between the two tubes water is caused to circulate. As shown, the tube *c* forms with the tube *b* an annular water supply conduit opening directly into the interior of the hollow main electrode *d*. In the embodiment here illustrated, this annular conduit is practically an integral extension of the main electrode. Water supplied to the conduit *c* thus first surrounds the tube *b* containing the igniting electrode and then passes into the principal electrode, although the opposite course can also be adopted.

As the igniting electrode *a* has a knife-shape it does not entirely fill the guiding pipe *b* and it is therefore necessary to provide a device to close the end of said pipe. For example, a sleeve *e* may be attached to the end of each igniting electrode, which sleeve is provided with an external screw thread engaging a corresponding internal thread within the pipe, and is also provided with a longitudinal opening of the same sectional size and shape as the igniting electrode. By turning the sleeve *e* about its axis the igniting electrode can be brought into an exactly vertical position, which is of advantage for the proper working of the apparatus. When the slot of the sleeve *e* is burned out or stopped up a new sleeve can easily be inserted.

What I claim and desire to secure by Letters Patent of the United States is:—

1. An electric furnace comprising, in combination, hollow main electrodes provided with annular water supply conduits leading thereto and forming integral extensions thereof, and longitudinally adjustable igniting electrodes jacketed by said annular conduits.
- 10 2. An electric furnace comprising in combination, main electrodes, pipes to supply water to cool said main electrodes, igniting electrodes passing through said pipes, pipes inclosing said igniting electrodes in said 15 water supply pipes, and a sleeve attached to the end of each said igniting electrode, substantially as, and for the purpose, set forth.
- 20 3. An electric furnace comprising, in combination, hollow main electrodes, water supply conduits leading to the interior of said electrodes, and igniting electrodes arranged within said conduits.

4. An electric furnace comprising, in combination, diverging hollow main electrodes, water supply conduits leading to the interior of said electrodes, and igniting electrodes adjustably arranged within said conduits.

5. In an electric furnace, in combination, a hollow main electrode, a water supply conduit leading to the interior of said electrode, a tube arranged within said conduit to form a water jacket therewith, and an igniting electrode arranged within said tube, said igniting electrode being adjustable longitudinally within said tube.

In testimony whereof I have signed my name to this specification in the presence of two subscribing witnesses.

HARRY PAULING.
